LOCK MECHANISM

Andrew Main, Cleveland, Ohio, assignor, by
mesne assignments, to Cleveland Fare Box and
Four-Way Lock Co., Cleveland, Ohio, a cor-
poration of Ohio

Application July 25, 1930. Serial No. 470,578

2 Claims. (Cl. 70—46)

This invention relates to locks, and more particularly to locks of the rotary plug and cylinder type. One object of the invention is to provide such a lock adapted for actuating a sliding bolt 5 and so arranged that full bolt movement in either direction requires full 360° rotation of the plug, making it possible to require insertion or removal of the key in one position only. Another object is generally to improve the plug and cylinder 10 mechanism in a manner to simplify and strengthen the same and also to take the driving effect of the key away from its wards for protecting the latter.

Further objects of the invention are in part 15 obvious and in part will appear more in detail hereinafter.

In the drawing, which represents one suitable embodiment of the invention, Fig. 1 is a plan view; Fig. 2 is a similar view with the cover and attached parts removed; Fig. 3 is a sectional elevation on the line 3—3, Fig. 1; Fig. 4 is a cross section on the line 4—4, Fig. 2; Fig. 5 is an elevation of the key; and Fig. 6 is a section on the line 6—6, Fig. 3.

The lock shown in the drawing is designed particularly for prison use, such as on solitary confinement cells, although it may be used for many other purposes. It comprises a base plate or body 1 which may be a simple metal plate or casting fastened to a suitable support. For example, in prison use it may be welded permanently along its edges to a metal plate of cell wall or door. Said plate carries the operating parts of the lock mechanism, which is housed in a casing 2 attached to plate 1 and includes a sliding bolt 3 having its locking portion guided in an opening in the casing wall, said bolt also having an elongated guiding slot or opening 4 through which extend the plug operated rotatable lock parts, comprising a connector 5 of sleeve form countersunk to receive a support, such as a disc like boss 1a of the plate 1, upon which the connector rotates. Said connector also is provided with an upper cylindrical recess 6 into which extends the inner end of the rotary plug 7, which is provided with a non-circular driving projection 8 entering a corresponding socket 9 in the connector 5 so that the latter partakes of all rotary plug movement.

Rotatably mounted on the connector 5 is a bolt 50 throwing member or roll back 10 having an arm 11 which cooperates with one or the other of two throwing abutments 12 and with stop shoulders 13 at opposite ends of curved surfaces 14 of a recess in the bolt. Fig. 2 shows these parts in lock released position, with the arm 11 against

a shoulder 13 and extending longitudinally of the bolt, so that the end of said arm forms a positive abutment for surface 14 to prevent bolt movement. In throwing the bolt to locked position, arm 11 is turned counterclockwise 180°, first engaging an abutment 12 in the position shown in dotted lines and then camming the bolt to locked position until arm 11 engages the other shoulder 13, the total arm movement being 180°. Reverse bolt movement is accomplished by the same amount of arm movement in the reverse direction.

The key for this lock is of special form, as will be described, making it highly desirable to compel an operator of the lock to always insert or remove the key in one position, and because the key must be turned to move the throwing arm it is clear that this desirable operation requires 360° rotation of the key. The driving connections from key to throwing arm therefore include a suitable lost motion connection so that 360° key rotation produces only 180° rotation of the roll back member 10. In the arrangement shown this lost motion connection is introduced between the connector 5 and the roll back 10. The former is provided with a projection 15 which turns or, more accurately, reciprocates back and forth in a recess 16 between two stop shoulders 17 of member 10. Therefore, assuming the parts in the position in Fig. 2 and that it is desired to throw the bolt to locked position, the connector is turned counterclockwise by the plug, the latter being operated by the key, as will appear. The first 180° of movement of the connector, during which the lug 15 moves from one shoulder 17 to the other, is an idle movement, without effect upon the roll back member, but the second 180° of its movement turns the roll back and throws the bolt. This action occurs in both directions of rotation from full locked to full release position and vice versa.

The casing or cover 2 carries a sleeve portion 18 into which is threaded a cylinder or barrel 19 in which rotates the plug 7 before referred to, said plug and cylinder being in general of the form and construction shown and described in my prior application for cylinder lock, filed October 17, 1929, Ser. No. 400,270, to which reference may be had for details not here described. The plug is provided with a cruciform key way or slot 20 for a key 20a having a warded portion of like cross section and whose wards actuate tumbler levers 21 cooperating with longitudinal grooves 22 of the cylinder. The plug is made of two parts, a body 23 and a cap 24, the body being of cy-

lindrical form carrying the integral driver 8 at one end and its tumbler slots being formed by two transverse diametrical saw slots 25 extending from its outer end toward the driver 8 at 5 its inner end, thereby forming four quadrant shaped segments 26 integrally connected only at one end. The cap 24 is countersunk and sleeved over reduced end portions of said segments with a driving fit and is preferably rigidly secured in any suitable manner to each one thereof, such as by a countersunk set screw 27. Said cap also is provided with a non-circular, such as square, socket 28 to receive a like shaped portion 29 of the shank of the key when the latter is fully inserted into the keyway in the plug. 10

With this arrangement, when the key is pushed fully home, the tumblers are entirely withdrawn within the plug, which is therefore free to rotate in its cylinder. Also the driving part 29 of the 20 key shank is in the socket 28. Therefore turning movement applied to the key is imparted to the cap and is distributed directly and equally to each of the segments 26. The cap 24 therefore not only tends to anchor the four segments immovably relative to each other, but also insures equal distribution of turning movement between them and prevents any possibility of bending or flexing of an individual segments, which might bind or otherwise interfere with the action 25 of the tumbler levers housed between them.

As stated the cylinder 19 is threaded into the sleeve 18. When screwed home it may be anchored non-rotatably by one or more screws 30 threaded through its flange into the sleeve, the 25 heads of such screws being countersunk in recesses 31 which are then filled with small brass plugs 31a which are ground off flush, and which must be bored out to open the lock. The plug is confined by a washer 32 which may be a driving fit or may be doweled into the cylinder as by the pins 33, and which washer has a single gateway 34 for a lateral lug 29a on the key compelling introduction or removal of the key in 40

only one position. As a result, the proper wards of the key always are registered with the proper grooves of the cruciform key slot of the plug.

Of course a lock of this kind is usually applied to that side of a door which is out of reach of the prisoner, to prevent his tampering with its parts. 80

What I claim is:

1. Lock mechanism of the character described, comprising a casing, a locking member movable to locked and unlocked positions, and actuating means therefor, including relatively rotatable cylinder and plug members, means for securing said cylinder against rotation relative to said casing, said plug member having four quadrant portions separated by crossed diametrical slots to form a cruciform key way, tumbler members in said plug, recesses in said cylinder adapted to receive said tumbler members, and a cap embracing the free ends of the quadrant portions of said plug and attached thereto, said cap being provided with a non-circular driving socket of cross section other than cruciform, whereby the quadrant portions of the plug and said cap are adapted to be separately driven by cruciform and non-cruciform portions of a key. 85 90 95 100

2. Lock mechanism of the character described, comprising a chambered casing having two opposite walls, the exposed wall being provided with an opening and the other wall with a support opposite said opening, a connector rotatable upon said support, relatively rotatable cylinder and plug members insertable into said chamber through said opening, a driving connection between said plug member and connector and attachable and detachable by endwise plug movement, a roll-back member surrounding the cylinder member and overlying and confining the connector upon its support, means for securing the cylinder member in the casing, and a locking member in the chamber of said casing actuated by said roll-back member. 105 110 115 120
